ALFRED J. ELLIS, OF WOODCLIFF-ON-HUDSON, NEW JERSEY, ASSIGNOR TO A. J. ELLIS, INC., A CORPORATION OF NEW JERSEY.

HOLLOW METAL DOOR AND THE LIKE.

1,039,371.

Specification of Letters Patent.

Patented Sept. 24, 1912.

Application filed March 4, 1911. Serial No. 612,226.

To all whom it may concern:

Be it known that I, ALFRED J. ELLIS, a citizen of the United States, residing at Woodcliff-on-Hudson, township of North 5 Bergen, in the county of Hudson and State of New Jersey, have invented certain new and useful Improvements in Hollow Metal Doors and the Like, of which the following is a full, clear, and exact description.

10 This invention relates to hollow metal doors, windows, and the like, and more particularly to an improvement in the construction disclosed in a co-pending application Serial No. 579,219, filed August 27, 1910, in 15 the names of Alfred J. Ellis and Charles E. Nellis. Among the essential features there-in presented were the provision of means for interlocking the respective elements of a door, or the like, with the further provision 20 of stiffening devices adapted to co-act with the interlocking portions aforesaid to space the same and to render the entire structure as rigid as possible.

I have now devised stiffening means which 25 are superior in many respects to those described in the aforesaid application, and which are adapted to co-act more efficiently with the novel interlocking flange construction used, to the end that a structure of far 30 greater strength is obtainable, while the cost of production is decreased. As in the foregoing case, the general construction is such that the securing devices or interlocking portions may be made of substantially uniform 35 sizes, even in doors or windows of different dimensions. These and other features of my invention will be hereinafter more particularly pointed out and set forth in the appended claims.

40 Referring to the accompanying drawings which form a part hereof and in which like characters designate like parts throughout the several views: Figure 1 is an elevation of a door constructed in accordance with the 45 principles of my invention. Fig. 2 is a vertical section of the said door taken on the line II—II of Fig. 1, portions of the panel and adjoining parts being broken away in order that the essential features may be 50 better illustrated. Fig. 3 is a fragmentary transverse section taken on the line III—III of Fig. 2; and Fig. 4 is a perspective detail of a fragment of one of the novel stiffening members employed.

55 In the drawings, the stiles of the door

have been designated 1, the upper rail 2, the middle rail 3, and bottom rail 4. Each of the said stiles is composed of a bent sheet of metal, substantially U-shape in cross section, the inner edges of which are folded over and then bent at right angles to the plane of such fold and thereafter again folded in such manner as to form on each side of the stile a plurality of grooved flanges, such flanges being preferably substantially normal to 60 each other. The rails also involve much the same construction except that I prefer to form the lateral plates thereof separate and distinct from each other instead of from a single plate as in the construction of the 65 stiles. This obviously, however, is merely a matter of detail. The size and shape of the flanges in both the rails and stiles are preferably identical, so that but few presses or rolls need be employed in the manufac- 70 ture of the parts of my doors, windows, or the like. Considering now the parts of the compound flanges in detail, the metal or other material of which the side of the stile or rail is composed is preferably folded back 75 upon itself as at 6, but the laterally disposed web 7 formed by the so folded material is spaced from the body of the member to provide a rather deep interiorly opening groove 8. These grooves I shall for convenience 80 designate channel grooves as they are intended to receive the flanges of the stiffening members, if such members be provided with flanges. The metal of the stile, rail, or like part is then bent substantially normal to the 85 surfaces of the webs 7 to form the inwardly directed webs 9; and finally the edges of these inner webs are shown as being bent or folded back over the bodies thereof to form recessed or grooved, interiorly directed 90 flanges similar to those just described, but substantially normal thereto. The folded edges of these flanges have been designated 95 10, and the grooves so formed 11.

Considering now the stiles more particu- 100 larly, I prefer to close the interior open sides thereof by stiffening members. These members may be of two forms, to wit, tongue carrying channel shaped members such as those shown at 12, or tongue carrying plate 105 shaped members such as those shown at 13. The only substantial difference between members 12 and 13 is that the members 12 have laterally projecting flanges 14 which are adapted to enter the grooves 8 above re- 110

ferred to, while the plate members 13 are unprovided with such flanges, but are, however, preferably of sufficient width to extend across the space between the inner walls of, for example, the rail forming plates. 5 In each case these stiffening members are provided with struck-up lugs or tongues 15 which are formed directly from the body of the member, said lugs or tongues being preferably substantially L-shaped as shown 10 in Fig. 4; so that a portion 16 of each tongue extends in substantial parallelism with the body of the stiffening member, and is spaced therefrom a sufficient distance to receive one of the inwardly directed grooved flanges above described between its under surface and the adjacent surface of the said body, as shown in Figs. 2 and 3. Grooves 8 and 11 preferably extend the entire length 15 of the stile or rail forming parts as the case may be, upon either side thereof, and are adapted for the reception of corresponding flanges upon the respective sections 17 of the molding and for the reception of other interlocking parts as described in my co-pending application aforesaid. In fact, except for the inclusion of the novel stiffening members above referred to, a door such as that herein described will be substantially 20 similar to that described in the aforesaid application, and, just as in the foregoing case, it has been my object to so form the respective interlocking parts as to provide practically homogeneous locking devices throughout the structure.

A door, or the like, constructed as herein shown may be assembled in much the same manner as described in my said former application; but by reason of the tongues now 40 provided on the stiffening members, it is herein necessary to slide a stiffening member in the direction of its length into position when positioning the same in the structure, in place of merely moving the simple 45 stiffening channel heretofore employed upwardly, downwardly, or laterally as the case might be, toward the respective inwardly directed flanges. A great advantage results, however, from this feature in that the channel-shaped stiffening members may now be 50 rigidly interlocked with the other parts of the door, window, or the like, instead of having a simple flange and groove connection therewith, which must be separately secured, as by welding, against lateral displacement. In my previously described construction set forth in the said former application, it was necessary to secure the stiffening member in place by welding, or the 55 like, whereas in the present construction the stiffening devices or members whether of plate or channel form cannot become displaced, and hence welding is not absolutely necessary. I prefer, however, to weld the 60 tongues 15 to the inwardly projecting 65

flanges with which they are in engagement, which may be readily accomplished since the said tongues are relatively narrow. The said preceding application described a welded connection involving the notching of the grooved flanges at their edges in order to afford access to a flange within the grooved flange, whereas I have now discovered that it is possible to do away with this notching of the parts and to weld the extremities of the respective aligned elements together on the lines where they interlock, directly at the extremities of such parts and before the same are slipped into position between the longitudinally extending elements, which in this exemplification of my invention are the stiles 1. In other words, I have now provided interlocking flange elements, the extremities of the interlocking flanges of which are welded together. As in the former case, if the structure in question be a door, the same may be provided with panels 18 and 19, panel 19, for example, being of asbestos or other suitable material, and panel 18 of glass. In the latter case it is desirable to provide means for readily removing or replacing the same, and the molding therearound may be hence formed as shown in Fig. 2, which construction is fully described in the said co-pending application, and it will hence be merely necessary to direct attention to a slight change herein necessitated by the provision of the tongues upon the corresponding stiffening members. As shown in Fig. 2 the tongues, at the right hand side of said figure, space the portion 19 of the molding 20 from the adjacent surface of the interiorly directed grooved flange whereas in the said former application such portion of the molding was preferably disposed directly in contact with such surface. The channel form of the stiffening member may be used where great strength is required, but in most instances the plate form of the same will be employed, as it is cheaper to manufacture and affords sufficient rigidity by reason of the provision of the flange engaging tongues. A door, for example, constructed like that shown herein is exceedingly strong and is practically absolutely fireproof, as it will be observed that all of the welded connections are covered by juxtaposed parts and are hence protected in case of exposure to intense heat.

The top and bottom edges of the door 120 herein disclosed are materially stronger and more rigid than the corresponding parts in the door set forth in the co-pending application aforesaid, in that herein not only is the improved stiffening member utilized as 125 shown in Fig. 2, but the cover plates 21 at the respective ends of the door are provided with L-shaped flanges the portions 22 of which are received by the corresponding grooves 11 of the inwardly directed flanges 130

of the rail plates 2, being slidably entered thereinto and spot welded when the door has been assembled.

It may sometimes be advisable to use the 5 tongued channel stiffeners in combination with the tongued plate stiffeners in the same structure, as shown in the accompanying drawing wherein the door has channeled stiffeners extending lengthwise thereof and 10 plate stiffeners extending across its width at suitable intervals.

In conclusion, I particularly wish to point out that I contemplate various applications 15 of my herein described invention, the door shown in the accompanying drawings being but one exemplification thereof, so that the said invention should only be limited by the scope of the claims appended hereto.

Having described my invention, what I 20 claim is:

1. In a sheet metal structure having substantially parallel opposed walls, sheet metal parts forming portions of said walls, each having a laterally extending flange, said 25 flanges being directed toward each other, and a sheet metal stiffening and spacing member for said walls, said member having offset tongues struck up from the body thereof, said flanges being received and 30 firmly held between the respective tongues and portions of said member adjacent to said tongue.

2. In a sheet metal structure, a plurality of substantially rectangular, juxtaposed parts having interlocking connections at 35 their respective abutting edges, some of said parts being disposed in substantial parallelism side by side intermediate others of said parts, the interlocking edges of the latter 40 extending over the line or lines of jointure of the said intermediate parts, said intermediate parts being welded together at the ends of said lines of jointure, and the said

other parts covering and protecting the 45 welds.

3. In a sheet metal structure, in combination, a sheet metal part having a portion thereof adjacent its edge folded back substantially into parallelism with the general surface of the part, the folded over portion 50 having a substantially ninety degree bend adjacent the folding line and the material between said bend and the edge of said part being further folded back upon itself to form a recessed flange, such flange extending 55 out laterally from the body of the part, the extreme edge of the part being spaced from the last mentioned folded portion to form together with the recess in the flange aforesaid a substantially L-shaped groove, a co-operating part adapted to enter said groove, and a stiffening member having an offset 60 tongue struck up from the body thereof, said tongue and other portions of said member being adapted to embrace the flange aforesaid therebetween.

4. In a sheet metal structure having substantially parallel opposed front and rear walls, flanged sheet metal parts forming 70 portions of said walls, and a sheet metal stiffening and spacing member for said walls, said member having offset tongues struck up from the body thereof, one of said 75 tongues being adjacent the front wall and another being adjacent the rear wall, flanges of the said sheet metal parts being recessed and firmly held between the respective tongues and portions of said member adjacent to said tongues.

In witness whereof, I subscribe my signature, in the presence of two witnesses.

ALFRED J. ELLIS.
